UNITED STATES PATENT OFFICE.

HERBERT STANLEY BRUCKSHAW, OF BOLTON, ENGLAND.

REINFORCED CONCRETE.

Application filed November 14, 1925. Serial No. 69,165.

This invention relates to reenforced concrete structures and more particularly to such structures as employed in the reinforcement of strong rooms, and in the manufacture of safes and doors which are required to offer resistance to burglarious attacks, both with hand tools and explosives.

Heretofore it has been proposed to use spiral metal coils embedded in concrete for the said purpose and it is the object of my present invention to provide an improved reinforcement of the type utilizing spiral springs, the said reinforcement being self supporting so that it can be readily transported, assembled and embedded in the concrete.

The invention comprises the improved combination and arrangement of parts hereinafter described and claimed.

Referring to the accompanying sheet of explanatory drawings:—

Figure 1 is an elevation and Figure 2 a plan view of a reinforcement in accordance with any invention.

The reinforcement comprises a plurality of rows of spirals *a*, each spiral being interwoven with the spirals at its opposite sides, and the spirals in one row being interwoven with the spirals in the adjacent rows. A structure so arranged has the disadvantage that it does not maintain itself in the extended condition shown in the plan view but the coils or spirals can close on one another. To overcome this defect, I interweave small diameter coils or spirals into two adjacent rows of spirals at the point where the latter are themselves interwoven. In the drawings small coils or spirals *b* are interwoven with adjacent rows of coils *a*. In

Figure 1, the positions of the small inter-

weaving coils or spirals between the second and third rows of spirals *a* are shown by the dot and dash figures *c*.

Rows of interwoven spirals *a* having the small interwoven coils *b* form a mattress and several mattresses can be connected together by intermeshing connecting coils *e* with the end coils of the mattresses and threading rods or bars *d* through the intermeshed coils as shown. The connecting coils *e* are of opposite hand to the coils they connect.

The coiled mattresses have the concrete formed therearound in any ordinary manner, but because of the employment of my invention, the correct extension or spacing of the rows of coils during concreting is ensured, and therefore a satisfactorily reenforced wall or like part is produced.

Claims—

1. A reenforcement for concrete comprising, in combination, a plurality of interwoven rows of interwoven spirals and means binding the rows together at places of inter-engagement.

2. A reenforcement for concrete comprising, in combination, a plurality of interwoven rows of interwoven spirals and spirals interwoven with the said rows at the places of inter-engagement.

3. A reenforcement for concrete consisting of a plurality of reinforcements as claimed in claim 1, and means for interconnecting the reinforcements including spirals intermeshing with the end spirals of the interwoven rows, and rods threaded through the intermeshing spirals.

In testimony whereof I have signed my name to this specification.

HERBERT STANLEY BRUCKSHAW.
